UNITED STATES PATENT OFFICE.

EUGEN KLEINER, WALTER BOKMAYER, AND OTTO HOFFMANN, OF MÖDLING,
AUSTRIA-HUNGARY, ASSIGNORS TO CLEMENT VINCENT HAWORTH, OF
OLDHAM, ENGLAND.

AIR-MOISTENING AND VENTILATING APPARATUS.

SPECIFICATION forming part of Letters Patent No. 511,897, dated January 2, 1894.

Application filed February 1, 1893. Serial No. 460,537. (No model.) Patented in Germany January 18, 1891, No. 58,902, and in England September 9, 1891, No. 14,765.

To all whom it may concern:

Be it known that we, EUGEN KLEINER, WALTER BOKMAYER, and OTTO HOFFMANN, subjects of the Emperor of Austria-Hungary, residing at Mödling, near Vienna, Austria-Hungary, have invented certain new and useful Improvements in Air-Moistening and Ventilating Apparatus, of which the following is a specification.

10 The invention has been patented in England, No. 14,765, dated September 9, 1891, and in Germany, No. 58,902, dated January 18, 1891.

This invention consists in various improvements in air-moistening apparatus (with which is combined a ventilating arrangement) whereby the consumption of water or other liquid used in such apparatus is reduced to a minimum and a powerful conveyance of air 20 to the ventilating space, or the space to be filled with moistened air, is obtained, and the liquid is also finely scattered, sprayed or vaporized without the formation of drops in the space in question, and in which the air drawn 25 into the apparatus is forced to pass through a curtain or cone of water and is thereby not merely washed but also saturated with moisture. In order to attain these results in this air-moistening and ventilating apparatus, we 30 cause two jets of liquid of preferably different sizes to play under pressure, upon each other in exactly opposite directions for the purpose of forming a hollow cone of water, whereby the air surrounding the apparatus is 35 not only powerfully drawn into the same but also a very fine comminution of the liquid is produced; and the air drawn in is saturated with the same.

In most of the moistening apparatus hitherto employed the comminution of the liquid 40 takes place by means of sprayers which are provided with numerous openings mostly of the thickness of a hair in size for the passage of the liquid which openings very soon become stopped up by the mineral impurities in the water and the impurities in the air whereby the continuous effective action of

the sprayer is considerably impaired and further these apparatus require constant supervision and cleansing.

50 The suction and pulverizing nozzle employed in this apparatus has only two proportionately large discharge-openings for the liquid which is to be comminuted so that no stoppage can take place or at least extremely rarely, because the impurities in the liquid even if they have not been already retained by the fine meshed filter sieve arranged in the supply pipe can pass freely through the 55 openings. By this means the action of our apparatus remains constant and reliable even when working for weeks without any expensive supervision and cleaning as in order to secure a faultless working of our apparatus it suffices from time to time, to cleanse the 60 filtering sieve box in the supply pipe which can be done in a few minutes and with little manipulation.

In order to allow of our invention being better understood, an air moistening and ventilating apparatus provided with the above 70 named improvements will now be more particularly described, reference being had to the accompanying two sheets of drawings, in which—

75 Figure 1 (Sheet 1) shows a vertical section of the apparatus on the line *f g* of Fig. 3. Fig. 2 is a vertical section on the line *d e* of Fig. 3. Fig. 3 is a plan of the apparatus. Fig. 4 shows separately and on a larger scale the 80 double nozzle employed to spray or comminute the water and draw the air into the apparatus. Fig. 5 (Sheet 2) shows a modified form of the apparatus.

85 Referring in the first place to Sheet 1 the apparatus consists of preferably a globular case *A* with a cylindrical neck *b* which ends in a flat cruciform shaped disk or shell *D*. This has four radial discharge passages *E* for the exit of the mixture of air and moisture 90 from the apparatus the spaces between each of the passages *E* being closed in by means of plates.

In the neck *b* there is placed a circular piece

R with cross bars which evenly divides the air saturated with moisture passing through the apparatus and allows the same to deposit in the form of drops any excess of moisture.

5 The point of a distributing cone G extends into the neck b the base of which cone lies in the plane of the cover of the shell D. The ends of a stirrup piece B are bolted or riveted at two opposite points of the neck b and this 10 piece serves for attaching the apparatus to the ceiling of the chamber which it is desired to ventilate. The case A has at its lower part a cylindrical projection c. The device for drawing air into the apparatus and for spraying the liquid and washing and saturating the air thus drawn in with the finely sprayed liquid is arranged in a cylinder C penetrating sidewise into the case A. This device consists of the two nozzles d d', Fig. 4 (carried 15 by one bracket) the nozzles being of preferably different diameters to which the liquid is conveyed under pressure by means of a pipe M the liquid emerging from the two nozzle orifices in the form of two jets of different 20 diameters and in exactly opposite directions. The nozzles are connected together by the pipe d''. Owing to these jets of liquid acting in opposite directions upon each other a hollow liquid cone or curtain (shown in dotted lines 25 in Figs. 1 and 4) is formed which vigorously draws the air into the apparatus through the upper opening in the cylinder C which may be controlled and adjusted as to size by means of the lid H. The air drawn in is forced to 30 traverse the cone or curtain of liquid or spray on its way through the cylinder C into the case A by which means it is not only washed and freed from all impurities but on its further course through the case A is also saturated with the pulverized liquid therein 35 contained and passes out of the apparatus in the finest subdivision through the passages E into the chamber which is to be ventilated. The liquid on its way to the double nozzle d d' 40 passes first through a filter box S Fig. 2 placed in the supply tube M and provided with a fine sieve. The liquid which collects in the case A in the form of drops passes through a valve i provided in the bottom plate J into 45 the return pipe N and is thus removed from the apparatus. The modification shown in section in Fig. 5 on Sheet 2 is a somewhat simpler arrangement of apparatus but does not differ essentially from that already 50 described. We provide a cylindrical casing k open at the top and bottom. The foot of the casing is splayed as at k' and rests upon supports l which separate the splayed foot of the casing for a certain distance from an inclined 55 flange m. Bolts n hold together the flange m, supports l and foot k'. Thus there is practically an open annular space between the foot k' and the flange m. In the center of the flange m there is formed a drip well o and 60 above the well o there is a cover p soldered to the upper end of the screw q which passes

through a nut r soldered to the flat bottom of the well. A conical wall s protects the screw and nut from the surrounding water. The cover p is of curved section as shown and 70 around the lower edge is a series of recesses p' which allow water to flow into the drip well o from the flange m. By turning the screw q the cover p can be raised so as to allow of access for cleaning purposes to the 75 well through the annular space. A pipe t takes away the deposited water from the drip well. The double nozzle d d' is situated near the top of the casing k and is supplied with water under pressure through the pipe u. 80 The apparatus is suspended by the bridle v. When the apparatus is in operation the cone spray produced by the double nozzle d d' is dashed against the side of the casing k and descends with the air which is drawn in at the 85 top to the foot of the casing where the mixture of air and water issues through the annular space as a fine mist or impalpable vapor, thoroughly moistening the atmosphere of the room into which it is discharged. The 90 water which may be deposited in the interior of the casing k flows down and is directed by the inclined ledge w to the drip well, and any moisture trickling down the under side of the foot k' is diverted by the arched slips x which 95 stand perpendicularly from the flange to fall upon the inclined flange m. We also form a secondary gutter by adding an outer extra ring y at the extreme edge of the flange m. This catches any condensed drops that might 100 have been blown to the edge of the ring. To purify the water and render the nozzles less likely to be choked by foreign matter in the water we pass the feed through a filter valve z.

We claim as our invention—

1. In combination, a mixing or saturating chamber having lateral delivery passages, an air inducting cylinder connected with said chamber and having an inlet opening for the admission of air and arranged to convey the same to the mixing chamber and the liquid spraying device located in the said air inducting cylinder, and arranged to force the air and liquid spray through the air inducting cylinder into the mixing chamber substantially as described. 105

2. In combination a mixing or saturating chamber having an outlet, an air inducting chamber connected with said mixing chamber and the spraying device consisting of the two jets of unequal diameter arranged in the air inducting chamber, said jets being arranged one above the other axially of the cylinder, the one being connected with the supply pipe and the two being connected to each other by a branch pipe d'', substantially as described. 110

3. In combination, the mixing chamber, the air inducting chamber connected therewith above the bottom of said chamber, and having an upper air inlet and a lower outlet leading to the mixing chamber, the lower part of

- said mixing chamber comprising a drip well, the outlet therefrom for the water, the outlet for the escape of the moistened air from the chamber above the lower part thereof and 5 the spraying device in the upper part of the air inducting cylinder and arranged to direct the spray downward and force the liquid with the air down into the mixing chamber substantially as described.
- 10 4. In combination, the mixing chamber A having lateral outlets at its upper end, the air inducting cylinder C, extending through the side of the mixing chamber and having an upper outer inlet opening and a lower 15 opening within the mixing chamber and the spraying and air inducting device arranged

within the air cylinder, substantially as described.

In witness whereof we have hereunto set our hands in presence of witnesses.
